CENTRALIZED TRAFFIC CONTROLLING SYSTEM

Robert M. Phinney, Rochester, N. Y., assignor to
General Railway Signal Company, Rochester,
N. Y.

Application March 31, 1932, Serial No. 602,231

1 Claim. (Cl. 175—320)

This invention relates to railway centralized traffic controlling systems and more particularly to a means for selectively sectionalizing the line circuit at various locations in such a system.

5 In certain selective types of railway centralized traffic controlling systems, a line circuit is employed consisting of two, three or four wires, as required, and extending through the various field stations of a system and normally connected together beyond the last of these field stations. A system of this type employs relays at each of these field stations in series with these circuits and it is obvious that the complete system is thrown out of operation by any trouble 10 in the line circuit, such as a broken wire. In many of such systems, a telephone line, such as used by the railroad train dispatchers, also extends throughout the section controlled by the centralized traffic controlling system and consequently may be available as a means for sectionalizing the series line circuit when in trouble 15 providing the telephone line is intact.

In view of the above and other considerations, it is proposed in accordance with this invention 20 to provide a means for selectively sectionalizing the line circuit of a selective centralized traffic controlling system at any one of several points to render that section of the system from the selected point to the control office operable. It 25 is further proposed to provide in this sectionalizing means a restoring means for again returning the series line circuit to its normal position after such line trouble has been corrected, and to also provide a local manual means for 30 operating the sectionalizing and restoring means at these various points.

Other objects, purposes and characteristic features of the invention will appear as the description thereof progresses, during which reference 35 will be made to the accompanying single sheet of drawing which diagrammatically shows a centralized traffic controlling system layout in connection with a sectionalizing means as proposed in accordance with the present invention and has been shown in a manner to make it easily understood rather than with the view 40 of showing the particular arrangement preferably employed in practice.

In the accompanying drawing, a line circuit 45 as employed in a centralized traffic controlling system, which may be of the type disclosed in the prior application of N. D. Preston et al., Ser. No. 455,304, filed May 24, 1930, is shown arranged to be sectionalized according to the present system. A system of this type is employed

to send controls to a plurality of field stations of which two are diagrammatically indicated by the dotted rectangles FS¹ and FS². A control office is indicated at one end of the system by the dotted rectangle CO with the line wires S, M and Com extending through responsive apparatus at each field station in series and connected together at the end of the system. It may be considered in this diagram that field stations FS¹ and FS² are the two stations located nearest the control office and that several other field stations are located between these points and the end of the line circuit.

A telephone line is indicated by the wires T and across these line wires a telephone selector, 15 such as indicated by the dotted rectangles S¹, S², etc., is connected at each field station except the last at which it is obvious that a sectionalizing means is not required. A telephone code transmitter indicated by the dotted rectangle CT is 20 also connected to these wires at the control office, and is operable to transmit a plurality of different codes, each one of which is effective to select a particular selector at a field station. These selectors and the code transmitter may be of the 25 conventional type employed in telephone practice or such as disclosed in the patent to J. C. Field, No. 1,354,814, granted October 5, 1920.

A contact 1 on the telephone selector is arranged to control the sectionalizing means, and this may be such as the one arranged to control the energization of the bell operating coils of the selector shown in Fig. 6 of the above-mentioned Field patent. Two relays A and C which can be considered, respectively, as initiating, and restoring relays, and which may be of the telephone type, are positioned by this contact 1 of the selector to effect the control of a relay B which can be considered a sectionalizing or cut-out relay, and which has contacts arranged to complete the centralized traffic controlling system wires S M and Com when this relay B is deenergized and are operable to connect these line wires together by the energization of the relay B as will be later described.

Now considering that trouble has occurred between field station FS¹ and field station FS², such as a broken wire, the operator, desiring to control apparatus at field station FS¹, operates the telephone code transmitter at the control office to 50 select the telephone selector S¹. This closes contact 1 momentarily and energizes relay A from a terminal of an energy source (+), contact 1, wire 2, back contact 3 of relay B, wire 4, through the winding of relay A, to an opposite terminal 55

of the energy source (-). Relay A then picks up closing its front contact 5, but relay B does not then pick up until the telephone selector S¹ has broken the circuit at its contact 1, inasmuch as it is obvious that the same potential of energy is placed on each side of the operating winding thereby preventing current from flowing in its coils.

However, as soon as the selector S¹ opens the contact 1, relay B is energized in series with relay A from (+), through back contact 6 of relay C, wire 7, front contact 5 of relay A, wire 8, through the windings of relay B, wires 9 and 4, through the winding of relay A, to (-). These relays A and B then remain energized through this circuit as long as relay C remains deenergized.

The line wires S and M are now connected together and to the common wire Com through suitable impedances IS¹ and IM¹ by the picking up of contacts 11 and 12 of relay B. These impedances IS¹ and IM¹ are to compensate for the impedance of the line circuit which is thereby cut out and obviously will be of various values at the field stations depending upon their location relative to the control office. A contact 13 of relay B is provided in the common wire Com which, when picked up, opens the common circuit from the control office to the system beyond the sectionalizing relay B and connects the common wire of this circuit which is cut off to ground for testing and/or protection purposes.

The centralized traffic controlling system may now be operated to control apparatus at the field station FS¹ inasmuch as the series circuits are now completed so far as that station. When a broken line wire beyond this point or such trouble in the circuit as may have occurred has been corrected, the operator at the control office may drop the relay B to again restore the operation of the complete system by again operating the code controller to select the telephone selector S¹. The operation of this selector S¹ for the second time, or with the relays A and B energized, then functions to pick up the relay C from (+), contact 1, wire 2, front contact 3 of relay B, wires 15 and 16, windings of the relay C, to (-). This opens the back contact 6 of relay C which interrupts the energizing circuit of relays A and B thereby effecting the restoring of the wires S, M and Com to their normal condition or including all apparatus to the end of the circuit.

A stick circuit for the relay C is provided by a front contact 17 which shunts around the front contact 3 of relay B thus maintaining the relay C energized after the dropping of relay B and until the circuit is broken by the opening of the selector contact 1. This contact 17 is necessary in the circuit, otherwise relay C might drop before contact 1 of the selector opened thereby again enabling the relays A and B to become energized and remain energized after contact 1 of the selector opened.

It may be found expedient to provide an aux-

iliary local push button such as PB¹, PB², etc. which is arranged in parallel with the selector contact 1, as shown. This push button is of the type which is biased to an open circuit position, and consequently its operation has the same effect on the relays A, B, and C as the selection of the telephone selector S¹, or, that is, a first operation thereof may sectionalize the centralized traffic controlling system at that point and a second operation may restore this line to its normal condition. It is to be understood that this push button is not essential to the system but its incorporation may be found convenient, inasmuch as it enables a maintainer, when discovering trouble or when repairing the line, to conveniently sectionalize the line circuit at that point without communicating with the operator at the control office.

A similar arrangement of relays and circuits is shown with distinctive exponents associated with the field station FS² and it is understood that each field station of the system except the last may be provided with such an arrangement. A sectionalizing system for railway centralized traffic controlling systems has thus been provided which enables an operator at the central control point or control office to sectionalize the line circuit at any one of various points in the system where it is found desirable because of the existence of an abnormal condition and such a sectionalizing system has also been provided which enables the operator by using the same arrangement of apparatus to again restore the sectionalizing means to its normal condition.

The above rather specific description of one arrangement of the present invention is given solely by the way of example and is not intended in any way whatsoever in a limiting sense. It is also to be understood that various modifications, adaptations and alterations may be applied to meet the requirements of practice without in any manner departing from the spirit or scope of the present invention as limited by the appended claim.

Having thus described my invention, what I claim is:—

In a control system; a relay bank including a first relay, a second relay and a third relay; a control contact; a pick-up circuit for said first relay including said control contact and a back contact of said second relay; a stick circuit for said first relay including the winding of said second relay, a front contact of said first relay and a back contact of said third relay; means including the pick-up circuit for said first relay for shunting the winding of said second relay; a pick-up circuit for said third relay including said control contact and a front contact of said second relay; and a stick circuit for said third relay including said control contact and a front contact of said third relay, said stick circuit for said first relay energizing said second relay only when said first relay is energized and said third relay is de-energized.

ROBERT M. PHINNEY.
